(57) **CLAIM**

The ornamental design for the sterile drape for an endoscopic camera, as shown and described.

DESCRIPTION

FIG. 1 is a left side perspective view of the sterile drape for an endoscopic camera according to the invention, showing the new ornamental design;

FIG. 2 is a left side elevational view thereof, the right-side elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.
